UNITED STATES PATENT OFFICE

HERMAN J. OSTDIEK AND CLARENCE J. OSTDIEK, OF MINNEAPOLIS, MINNESOTA,
ASSIGNORS OF ONE-TENTH TO MARY E. HANKE

MOP

Application filed August 5, 1929, Serial No. 383,519. Renewed July 16, 1931.

This invention relates to mops and particularly to an improvement on the mop disclosed in Patent No. 1,545,510, issued conjointly July 14th, 1925, to Herman J. Ost-
5 diek, (one of the applicants herein) and Mary E. Hanke. The invention is particularly directed to detachable means for connecting the elastic swab holder with the mop head.

10 It is an object of our invention to provide in a mop of the general class disclosed in said Patent #1,545,510, means for very quickly connecting and disconnecting the elastic swab holder with the head of the mop whereby 15 mop swabs may be quickly and easily replaced or removed for laundering.

20 A further object is to provide a simple but highly efficient mop construction which will add little, if any, expense to the structure disclosed in said Patent #1,545,510 but which will provide an efficient mop wherein a coiled spring or other elastic element on which the swab is mounted may be disconnected from the head by a short longitudinal and subsequent torsional movement of the elastic swab 25 holder.

These and other objects and advantages of the invention will be apparent from the following description made in connection with 30 the accompanying drawings in which like reference characters refer to similar parts throughout the several views and wherein:

Fig. 1 is a plan view of an embodiment of the invention, a portion of the swab being 35 broken away to disclose the coiled spring swab holder therewithin.

Fig. 2 is a fragmentary plan view of the mop head and associated parts on a larger scale;

40 Fig. 3 is a cross section taken on the line 3-3 of Fig. 2;

Fig. 4 is a fragmentary plan view of a slightly different embodiment of the invention, showing the mop head and terminals of 45 the coiled spring swab holder; and

Fig. 5 is a fragmentary elevation looking in the direction of the crotch portion of the mop head.

50 Our improved mop, as illustrated in the drawings, includes the usual elongated han-

dle 6 preferably constructed from a suitable wooden pole. To one end of said handle, a Y-shaped hollow attachment head is secured by suitable means, such as a screw or bolt 6a said head comprising a central, handle receiving socket 7 and a pair of spring receiving sockets 8 which diverge oppositely from handle socket 7, sockets 8, as shown, defining an angle of approximately 90° although, of course, this angle may be varied. Sockets 8 are substantially tubular and each is provided with a longitudinally extending entrance slot 8a, said slots extending from the outer ends of said sockets inwardly for a considerable distance, widening laterally at their inner extremities, as indicated by the numeral 8b. The said widened inner extremities 8b are extended longitudinally in an outward direction relatively to the sockets 8 and at opposite sides of the entrance slots 8a, thereby forming for each socket a pair of pin retaining notches 9. The inner and widened portions 8b of the sockets are also each provided with an outwardly projecting inverted V-shaped portion 10, the apex of the V being substantially alined with the center of slot 8a, the oppositely sloping sides of the V-shaped portions constituting guiding or camming surfaces 10a. The complete slots thus formed are substantially of inverted T-shape and afford bayonet joints as will hereafter more fully appear.

The slots may be easily formed by cutting the tubular or semi-tubular members constituting the sockets 8 and we prefer to provide the slots for the two spring receiving sockets in opposite faces of the attachment head. The reason for this is that the most practicable and economical way of making the attachment head above described is to stamp the same from sheet metal in two duplicate sections thereby requiring only a single die, said sections having web-like flanges 11 extending between their several semi-sockets whereby the sections may be easily united by spot welding or otherwise joining the flanges 11 of the complementary sections.

The mop swab indicated as an entirety by the numeral 12 is of any suitable structure and may be made up of a multiplicity of short

yarn or cord sections fastened to a strip of suitable material such as cloth or canvas, the said material being doubled to form a tubular hem 13a through which a flexible swab holder is passed, the ends of the swab holder being detachably secured in the two sockets 8.

While it will be understood that we may employ any flexible swab holding element which has elasticity and durability, we prefer a cylindrically coiled spring 14 of sufficient length to form a substantial loop when doubled. As illustrated, the extremities of the coiled spring 14 are projected radially outward to afford lock pins 14a which cooperate with the bayonet slots previously described and are seated, when in locked position, in the pin retaining notches 9 at the sides of slot 8a. If means other than the coiled spring is utilized for holding the swab, such as rubber tubing or flexible metal tubing, the extremities of the holding elements may be provided with laterally extending pins corresponding to the pin extremities 14a of the coiled spring 14 illustrated.

As shown in the drawings, a short compression spring 15 is mounted in the central and communicating portions of sockets 8 for the purpose of applying retaining pressure against the extremities of the swab holding spring 14, although in most instances, the torque of the coiled swab holding spring is sufficient to retain the extremities thereof in locked position without the use of compression spring 15.

To detachably connect the coiled spring swab holder 14 with the sockets 8 of the attachment head, one end of spring 14 is first inserted in the socket, its locking pin 14a being projected longitudinally inward through one of the slots 8a until it is guided by one of the camming edges 10a of the V-shaped projecting portion 10 to one side or the other of slot 8a. The pin is then engaged by the appropriate locking notch 8b and the swab applied to the free end of the spring 14 by passing the spring through the hem portion 13a of the swab. The free end of the spring 14 is then twisted slightly in either direction and its locking pin 14a is inserted in the slot 8a of the unoccupied socket, being guided to position by one of the camming surfaces 10a. The torque applied to the spring 14 by twisting the same, will cause locking pin 14a to turn to one side of the cooperating widened slot portion 8b out of alinement with the entrance slot 8a, resulting in said pin being seated in one of the pin-receiving notches 9. The direction in which the pin 14a turns upon passing the extremity of entrance slot 8a depends, of course, upon the direction of twist applied to the spring. When manual pressure has been released from the spring the tendency of the twisted coiled spring to straighten out will cause the extremities

thereof to exert a slight outward pull against the locking notches.

In Figs. 4 and 5, a slightly different embodiment of the invention is illustrated. Here the tubular spring-receiving sockets 8 are provided on opposing sides, that is, on the upper portions in the drawings, adjacent the crotch portions of the Y-shaped head, with inwardly and longitudinally extending L-shaped bayonet joint slots, each of said slots comprising a straight entrance portion 20 extending inwardly and longitudinally from the outer end of one of the sockets 8 and having a lateral extension 20a which is disposed circumferentially of the socket. At the extremities of the lateral extensions 20a longitudinally and outwardly projecting pin-engaging notches 20b are provided for receiving the pins 14a of the coiled swab holding spring or other elastic swab holding elements. A compression spring 15 is provided in the central and communicating portions at the inner ends of sockets 8, which is adapted to engage against the extremities of the swab-holding spring 14 to assist in preventing disconnection of the swab holding spring 14.

The attachment head of the last described device is also preferably made of two duplicate sections or stampings provided with the welding flanges 11 generally similar to the welding flanges of the form of the invention first described.

From the foregoing description it will be seen that we have invented an inexpensive but highly efficient improvement in mop construction having all the advantages of the mop disclosed in the patent to Ostdielk and Hanke #1,545,510, with the additional advantages that the elastic swab holding element may be instantly connected or disconnected from the attachment head whereby a new swab may be attached or a swab removed for cleaning. It is often desirable in a mop to utilize one swab for applying water or other liquid to the floors, while a different swab may be employed for oil or dressing.

It will, of course, be understood that various changes may be made in the form, details, arrangement and proportions of the various parts without departing from the scope of the invention.

What is claimed is:

1. In a mop, an attachment head having a pair of outwardly projecting spaced sockets, a mop swab, an elongated swab holding element which is resilient and may be placed under torque the ends of said swab holding element being adapted to be seated in said sockets, one end of said swab holding element having a lateral projection which is adapted to interlock with means in one of said sockets, the torque of said resilient element retaining said projection against disengagement from said means.

2. A mop head having diverging sockets

formed with bayonet slots, in combination with a mop swab and an elongated swab holder that is resilient and may be placed under torque, and having lateral projections 5 near its ends that are insertable into said sockets for interlocking engagement with the bayonet slots thereof.

3. A mop head having diverging sockets formed with bayonet slots, in combination 10 with a mop swab and a swab holder that is resilient laterally and in torque and having bayonet lock projections near its extended ends that are insertable into said sockets for interlocking engagement with the bayonet 15 slots thereof, the bayonet slot in one socket having a laterally offset swab holder retaining portion extending in one direction and the bayonet slot in the other socket having a laterally offset swab holder end retaining 20 portion extending in opposite direction.

4. A mop comprising a head having a handle-receiving socket and two diverging spring-receiving sockets, said spring-receiving sockets having longitudinal entrance 25 slots with inner extremities extending in opposite directions to afford bayonet slots, in combination with a mop swab, and a swab holder in the form of a cylindrically coiled spring applied to said swab and at its extended ends having out-turned portions 30 insertable into the spring-receiving sockets through the longitudinal slots thereof and into the inner extremities of said slots, the torque in the spring being such as to maintain interlocking engagement between the outer ends of the said spring and the reversely 35 extending inner extremities of said slots.

5. A mop including a head having a handle-receiving socket and two diverging spring-receiving sockets, said spring-receiving sockets having bayonet slots comprising longitudinal entrance slots with their inner extremities terminating in laterally widened 40 portions extending from both sides of the entrance slot, in combination with a mop swab and a swab holder in the form of a cylindrically coiled spring applied to said swab and at its ends having out-turned portions insertable into the spring-receiving 45 sockets through the longitudinal slots thereof and into the widened inner extremities of said slots, the particular side of the widened portion of each slot in which a co-operating out-turned spring end will find interlocking engagement being dependent upon the direction 50 of torque in said spring.

6. A mop head having sockets formed with bayonet slots, in combination with a mop swab, a swab holder in the form of a coiled 55 spring applied to said swab and having extending portions provided with outwardly extending projections insertable into said sockets for interlocking engagement with the bayonet slots thereof, and a compression 60 means in said sockets and engageable with

the lower ends of the spring for exerting an outward locking pressure thereon.

7. In a mop, a handle, an attachment head secured to one end of said handle having a pair of outwardly projecting spaced sockets, 70 an elongated flexible swab holding element, the ends of which are seated in said sockets, a mop swab, at least one of said sockets and one of the ends of said swab holding elements having cooperating interlocking means 75 whereby one end of said swab holding element may be instantly connected with or disconnected from said attachment head.

8. In a mop, a handle, an attachment head secured to said handle and having a pair of spaced sockets, an elongated flexible swab holding element, the ends of which are seated in said sockets, one of said sockets having a bayonet slot therein, the entrance of said slot extending substantially longitudinally 85 of said socket and one end of said swab holding element having a lateral projection having locking engagement with the returning portion of said bayonet slot.

9. The structure set forth in claim 8 and a compression means in said slotted socket for exerting outward locking pressure on the adjacent end of said swab holding element.

In testimony whereof we affix our signatures.
